TOILET SEAT

Albert Calderon, Atlanta, Ga.

Application April 15, 1948, Serial No. 21,111

5 Claims. (Cl. 4—237)

1

This invention consists of an improved toilet seat and means or a device which has for its object three main purposes; (1) for facilitation of the excretion of the waste from the human system; (2) for the saving of toilet paper; and (3) for sanitation.

An object is to provide an improved toilet seat which is simplification of the device and structure shown and described in my prior application for patent on Toilet Seat, Serial No. 19,272, filed April 6, 1948, and more particularly with reference to the means for causing movable or slideable sections interposed in opposite sides of the seat, to be normally held in, in alignment with respect to the widths of said sides, and to slide or shift outwardly under the weight of a person reposed on the seat in use, to cause the thighs and buttocks to be spread, separated or pulled apart and the area surrounding the rectum to be stretched when excreting fecal material, to facilitate and ease excretion of waste material so as to maintain said area or parts as well as the seat and bowl in clean and sanitary condition by reason of confining the excretion and saving on the use and expense of toilet paper.

Another object is to provide a toilet seat with slideable sections at the sides, adapted to move in and out on inclined planes, means being provided to normally cause the sections to move upwardly and inwardly on said planes to positions in alignment with the sides of the seat when the latter is not in use and said sections adapted to move outwardly and forwardly with respect to each side of the person using the seat to pull apart, spread or separate the thighs and buttocks and stretch the area surrounding the rectum thereby facilitating excretion of waste material and preventing contact of the fecal material with parts surrounding the rectum to retain the same clean and save toilet paper.

With the above and other objects in view, my invention consists in the arrangement, combination and details of construction disclosed in the drawing and specification, and then more particularly pointed out in the appended claims.

In the drawing,

Figure 1 is a top plan view of a toilet seat equipped with the improvement in accordance with my invention, the movable section on one side being removed;

Figure 2 is an enlarged cross section of one side of the seat, taken on the line 2—2 of Figure 1; and

Figure 3 is a detail section taken on the line 3—3 of Figure 2.

2

Referring to the drawings, 10 designates a toilet seat of conventional character and any suitable durable material, having the bight portion 11 attached at the back edge to a closet bowl in any desired manner, and provided with arcuate sides 12 terminating in spaced forward ends 13, so that the seat as shown is of substantially horseshoe shape. The sides 12 of the seat 10 intermediately or at the points of greatest lateral curvature or projection are provided each with a transverse forwardly angled slot or recess 14 in its upper portion so that the two slots diverge forwardly in obtuse angled relation to each other to receive similarly related oppositely inwardly and outwardly slideable or movable top plates or sections 15 each provided with roughened, criss-cross or corrugated top surfaces 16 so that surface friction with the thighs and buttocks of a person reposed or sitting on and using the seat, is increased.

The front and rear ends of the slots, recesses or grooves 14 and the corresponding coacting and interfitting ends of the sections 15 at each side, are parallel and extend diagonally entirely across the sides 12 from the inner edges to points adjacent or short of the outer edges thereof forwardly from the inside to the outside and said sections conform to the curvature, shape and plan of the portions of the sides 12 determined by the ends of the slots 14 and are concave on the inner edges and convex on the outer edges the same as sides 12.

The slots 14 extend entirely across the thicknesses of sides 12 which as with the entire top face or surface of the seat 10 are generally convex as indicated at 16 and flat and on a horizontal plane at the bottom face or surface as at 17 including the base or bottom portions below slots 14, the contour at the top and cross-section being such as to best conform to and comfortably seat a person reposed on and using the seat. Also, the inner edges 18 may be slightly rounded or convex and substantially vertical while the seat tapers in thickness cross-sectionally from the inside to the outside at the convex top surface 16.

The bottom surfaces of the slots 14 slope or incline generally outwardly, the longitudinal bottom inner portions or top surfaces 19 thereof for the lengths of the slots of less than half the width of the slots and seat sides, sloping from a point substantially intermediately of its height or thickness but preferably slightly below the halfway point being inclined downwardly toward the outside but terminating short of the transverse center or less than half the width of the

sides 12 or cross section thereof and terminating in a shallow or short vertical wall or surface forming an inwardly facing shoulder 20. From this point, the bottom of the slot 14 or top surface of the bottom wall thickness formed by the slot, is inclined or sloped in an opposite direction or inwardly as at 21, being elevated toward the outside and terminating in such direction by a similar but shallower short vertical wall or surface forming a second outer inwardly facing shoulder 22 still slightly inwardly of the transverse centers of the sides 12 but medially to a vertical outer wall or surface 23 formed by a vertical cut-out or recess 24 in the sides 12 at the outer ends of the slots 14. The top surfaces 25 from walls or surfaces forming inwardly facing shoulders 22, incline or slope outwardly to outwardly facing vertical walls 23, in inclined planes parallel to the inclined planes of the inner portions or surfaces 19 but oppositely at the opposite sides 12 of the seat 10.

The sections 15 are similarly formed to oppose the bottom portions of sides 12 of reduced thickness where said sides are provided with the slots 14, that is, the bottom portions constitute the lower half portions or thicknesses of the wall portions of the sides 12 at the slots 14 integral with the remaining portions of the seat, while the plates or sections 15 constitute the upper half portions or thicknesses of the wall portions of the sides 12 at the slots 14 therein. The bottom surfaces of the section 15 have outwardly sloping or inclined inner portions or bottom surfaces 26 at the inner portions of the sides of the seat of greatest thickness or vertical dimension, but transversely or cross-sectionally, surfaces 26 and the depending inner portions of sections 15 forming the same, are spaced from, parallel to, and more shallow, shorter or narrower transversely than the opposed similarly inclined top surfaces 19 and terminate in outwardly facing shallow or short vertical walls or surfaces forming shoulders 27 opposing and parallel to wall surfaces or stop shoulders 20. From the upper ends of shoulders 27, inwardly inclined bottom surfaces 28 are provided considerably spaced from, opposing and parallel to surfaces 21 but located normally inwardly of or in inner vertical planes and higher horizontal planes and above same in offset or staggered relation with respect to their inner and outer ends or marginal limits extending diagonally as shown in Figure 1. Surfaces 28 terminate at short or shallow vertical walls or surfaces forming outwardly facing shoulders 29 spaced from and parallel to surfaces or shoulders 22, and from their upper ends, outwardly sloping or inclined bottom surfaces 30 are provided slightly spaced above and parallel to surfaces 25 and terminate in vertical walls of the inner sides of cut-outs or recesses 24 in alignment vertically with lower edge walls 23 of the bottom portions of the sides 12 at slots 14. Cut-outs or recesses 24 extend beyond the sides of the slots 14 at their ends and conforming upwardly reduced or tapered sections 31 form cover plates or lids of substantially segmental or sector-shape with flat inner vertical faces 32 fitting surfaces 23, flat bottom faces 33 aligned with surfaces 17, and convex outer and top surfaces 34 conforming and merging in top surfaces 16. The ends of sections 31 project beyond the slots 14 and seat in the ends of cut-outs 24 as seen at 35 in Figure 1 to form stops or shoulders to limit the inward movement of sections 15 in their sliding action and normal positions. Sections or fill-ins 31 may be cut or

parted from sections 15 or otherwise formed and attached thereto in any suitable manner as by screws 36.

Slidable sections 15 have pairs of inclined parallel end ribs 37 slidable in guideways or grooves 38 in the vertical walls of slots 14 in which sections 15 are loosely received and move with a sliding fit. Anti-friction means are provided between sections 15 and the bottom portions of sides 12 formed by slots, recesses or grooves 14, and more particularly between inclined surfaces 19 and 26, and 25 and 30, respectively. As shown, spaced parallel anti-friction cylinders or rollers 39 are journaled at their ends or shafts in and carried by section 15 at semi-circular grooves 40 in surfaces 26 to roll on surfaces 19, or vice versa, and similar spaced parallel cylinders or rollers 41 are journaled at the bottom walls formed by slots 14, in semi-circular grooves 42 in surfaces 25, to roll against surfaces 30 or on which the latter move, or vice versa.

In this way, sections 15 at opposite sides 12 of the seat are adapted to move out and down the inclines, and in and up same, in opposite directions. However, sections 15 are normally held in and up or in raised positions aligned with sides 12 as by any number of springs 43 having their ends seated in sockets or countersinks or counterbores 44 to retain the springs in position to normally move the sections inwardly, upwardly and rearwardly and raise them in their guideways or sliding mounts to positions in alignment with sides 12 at slots 14.

Normally, a person has to excrete the waste from his body twice daily and these operations cause more or less strain. This strain which is detrimental and unfavorable takes one form or another, for example separating the thighs and squeezing the stomach, or by pulling apart the buttocks with the hands and at the same time bending forward. By using this invention, one does not have to contend with the above mentioned discomforts. As soon as one sits on this seat of horseshoe shape, the buttocks rest on plates or sections 15 of sides 12. Owing to the weight of the person exerted on these sections or plates they will slide outward because each of these plates rests on inclined planes built in the base of the seat. The cylindrical rollers facilitate the sliding of plates or sections. The springs which are held in position by the two pairs of countersinks 44 are used to bring back the sections or plates as soon as the weight is removed from it. When a person sits on the seat, automatically the plates move outward and owing to the corrugated surfaces friction is increased, thus the buttocks are stretched apart.

This separation of the buttocks first facilitates the excretion of the waste. Practically always people dirty not the rectum but the surrounding area of the rectum when excreting fecal material. Therefore, the surroundings being stretched by the present improved toilet seat, are freed from contacting fecal material, thus saving toilet paper. The latter being true also accomplishes the second purpose of this device. The third purpose of the device, for sanitation, is accomplished through the elimination of the act of cleaning the surrounding area of the rectum. This device therefore is helpful in excreting the waste, very sanitary and most economical.

Although the seat as shown in the drawings is round or substantially round, the preferred form is substantially oval in shape; therefore, it will

be understood that the shape can be either oval or round, but preferably oval.

I do not mean to confine myself to the exact details of construction herein disclosed but claim all variations falling within the purview of the appended claims.

What I claim is:

1. An improved toilet seat comprising a body having spaced apart side portions, upwardly opening transverse stepped slots formed in said side portions, the bottom surface of each of said slots being inclined outwardly and downwardly and including intermediate vertical portions, a separate seating section disposed in each of said slots and having a lower surface complementary to said bottom surface, and resilient means disposed between the vertical portions of said section and said slot and adapted to constantly urge said section inwardly and upwardly whereby said sections are normally disposed inwardly and upwardly and are moved outwardly and downwardly by the weight of a person positioned on said seat and said sections.

2. An improved toilet seat comprising a body having spaced apart side portions, an upwardly opening transverse stepped slot formed in the top of each of said side portions, the bottom surface of said slot being inclined downwardly and outwardly and including intermediate vertical portions, a movable seating section in each of said slots, the lower surface of each of said sections being complementary to said bottom surface and inclined downwardly and outwardly for slidable engagement with said slot bottom surface, resilient means disposed between the vertical portions of each of said slots and the associated movable section and adapted to constantly urge said section inwardly and upwardly, and means de-

pending from said section adapted to engage said side portion for limiting the inward movement of said section.

3. An improved toilet seat as set forth in claim 2 wherein the front and rear walls of said slots are formed with elongated grooves therein extending parallel to said slot bottom surface, and said sections include flanges on the opposite ends thereof slidably engaging in said grooves to prevent removal of said sections from said slots.
4. An improved toilet seat as set forth in claim 2, wherein anti-friction means are disposed between said section bottom surface and said slot bottom surface.
5. An improved toilet seat comprising a body having spaced apart side portions, a transverse upwardly opening slot formed in each of said side portions, a movable section disposed in said slot, said slot and said section being formed with stepped outwardly and downwardly inclined slidably confronting bottom surfaces, the steps of said bottom surfaces being adapted to abut each other for limiting the outward motion of said section, spring means interposed between said steps for constantly urging said section inwardly and upwardly, and means depending from said section and adapted to engage said side portion for limiting the inward motion of said section.
